(57) **CLAIM**

The ornamental design for a turned-out line taps for high voltage electric power switch, as shown and described herein.

DESCRIPTION

FIG. 1 is a perspective top view of turned-out line taps for high voltage electric power switch.

FIG. 2 is a front side view of the turned-out line taps for high voltage electric power switch.

FIG. 3 is a right side view of the turned-out line taps for high voltage electric power switch.

FIG. 4 is a left side view of the turned-out line taps for high voltage electric power switch; and,

FIG. 5 is a top view of the turned-out line taps for high voltage electric power switch.

The broken line portion of the figure drawings is included to show portions of the article that form no part of the claimed design.
